WILLIAM S. HENRY, OF ROCHESTER, NEW YORK, ASSIGNOR TO GENERAL RAILWAY SIGNAL COMPANY, OF GATES, NEW YORK, A CORPORATION OF NEW YORK.

DYNAMIC RETURN INDICATION-SIGNAL.

1,127,436.

Specification of Letters Patent.

Patented Feb. 9, 1915.

Application filed June 22, 1911. Serial No. 634,666.

To all whom it may concern:

Be it known that I, WILLIAM S. HENRY, a citizen of the United States, and resident of the city of Rochester, in the county of Monroe and State of New York, have invented a new and useful Dynamic Return Indication-Signal, of which the following is a specification.

This invention relates to a semi-automatic signal, and particularly to a semi-automatic signal used in connection with a mechanical interlocking machine.

The object of this invention is to so arrange the circuits and controlling connections to a semi-automatic signal, that a dynamic indication can be obtained therefrom successfully without the use of complicated lever locks and circuits controlling the same.

The invention consists in the arrangements and combinations for attaining the desired result, one form of which is used to illustrate the principle involved.

In order that a complete understanding of the principle of my invention may be had, a desirable arrangement embodying the principle, making use of well known instrumentalities is illustrated in the figure of the drawing accompanying this specification, and on said figure the different parts are designated by numerals, similar parts being designated by like numerals and the parts so designated being referred to in the specification by such numerals.

Construction.—1, designates a core of soft iron about which is wound the wire 2, the two elements thus constituting an electromagnet of which 3 designates the armature which is fastened to an arm 4 of a lever, the other arm of the lever being designated by 5, and the lever being pivoted on the pivot pin 6, the end of the lever arm 5 bearing a dog 7 which is adapted to coöperate with a sector 8, which sector has a link 9 attached thereto which is adapted to be connected to the rocker or similar part which actuates the mechanical locking of any type of mechanical interlocking machine.

10, 11 and 12 designate conducting arms which are adapted to be moved into and out of contact with the metallic contact strips 13, 14 and 15 and being caused to thus act by the movement of the sector 8 upon its pivot 16, by reason of the movement of the

latch of the lever of a mechanical interlocking machine the rocker or similar part of 55 which is connected to link 9.

All of the above described parts are well known in the art and are fully described in application Serial No. 625,859, filed May 8th, 1911, of William S. Henry, in which application is further fully described and illustrated the construction and mode of operation of the latch 17, which coöperates with the dog 7 to retain the dog 7 in the unlocking position after being raised by the energization of the electromagnet whose core is 1, whose helix is 2, when the sector 8 is moved to a position corresponding to the normal position of the lever of the mechanical interlocking machine to which it is connected, with the latch of the mechanical interlocking machine lever in raised position.

18 and 19 designate the two cores of an electromagnet joined together at one end by the yoke 20 and having in operative relation with the other ends an armature 21 and having each two coils of wire wound thereon, which coils of wire are designated by the numerals 22, 23, 24 and 25; coils 22 and 25 being connected together and the coils 23 80 and 24 being connected together, the whole constituting what is called the "hold clear mechanism" fully shown and described in the patent to Winthrop K. Howe, #985,677, dated February 28, 1911, and which is intended to hold the signal arm in any one of its moved positions as the full clear or 90° position or in the 45° or caution position as is well known and understood in the art.

26 designates a motor armature connected by a train of gears and power storing mechanism to the signal 27 as fully shown, described and claimed in the application of Winthrop K. Howe, Serial No. 609,417, filed February 18th, 1911.

28 designates the field of the motor of which 26 designates the armature; 29 designates a snubbing resistance which by means of switch 30 acts as an electrical dash pot 100 to restrain undue speed of the signal arm in returning to either the 45° or 0° position of the signal blade and is fully shown, described and claimed in the application of Winthrop K. Howe, Serial No. 564,018, filed May 28th, 1910.

31 designates a relay controlled by a track circuit in advance of the signal in a manner well known and understood in the art.

32 designates what is called "the line control relay" and is controlled by the signal in advance of the signal governing the track section controlling the relay 31.

33, 34, 35 and 36 designate diagrammatically the movable member of a circuit breaker which moves in unison with the signal arm 27; 37 designates the movable member of a circuit breaker which is, what is called, a "snap" circuit breaker, for it does not move synchronously with the movement of the signal arm, but makes its movement with a snap, that is, in the particular case under consideration, the arm 37 does not move from the position shown in the drawing until the signal mechanism has moved through a very considerable arc when it is then tripped, being before latched up, and completes its movement instantaneously, all of which is fully shown and described in the pending application of Winthrop K. Howe, Serial No. 609,417, heretofore referred to, which also shows an exact mechanical construction which the circuit breakers herein shown diagrammatically and designated by numerals 33, 34, 35 and 36 may take.

30 The signal herein shown and described and the mechanism for moving the signal, as is the case in the application of Winthrop K. Howe, Serial No. 609,417 heretofore referred to, have a lost motion of 40° between them so that when power is applied to the motor to actuate the signal, the mechanism travels 40° before any movement of the signal blade takes place, in which period of free movement the power storing mechanism stores power to move the mechanism backward,—as fully described in the application of Howe, Serial No. 609,417, heretofore referred to.

I shall herein designate the position of all parts when in the position as shown in the figure as the -10° position, except the signal blade 27, the position of which will be designated as the 0° position. By such nomenclature all positions of the mechanism which are assumed while the blade 27 is at the zero position will be designated as certain minus degree positions. All positions assumed during the movement of the blade 27 will be designated in correspondence to the position of the blade.

The arm 33 has a movement from the position shown to a position coinciding with dash line 39 before any movement at all of the signal blade 27 takes place, and also is 60 in contact with strip 38 during the first three degrees of the movement of the signal arm when moved from the zero position toward the proceed position; arm 34 contacts with strip 40 during the movement from -3° to -1° and with strip 41 from 25° to

44° in the position of the signal blade; arm 35 contacts with strip 42 from -3° to -1° with strip 43 from 42° to 44° and with strip 44 from 87° to 89° ; arm 36 contacts with strip 45 from -3° to 2° and with strip 46 from 42° to 47° and with strip 47 from 87° to 92° .

Arm 37 being a snap arm does not move at all during the preliminary 40° movement of the mechanism but when such movement is completed, the arm 37 snaps from in contact with strip 48 to contact with strip 49, it then moves synchronously with the movement of the signal blade, breaking contact with strip 49 at the 45° position of the blade, 80 making contact with strip 50 at the 43° position dragging over strip 50 and breaking contact therewith at the 87° position of the blade. Upon returning, the arm drags over strip 50 and strip 49 until the signal blade comes to the zero position and it remains in contact with strip 49 until the mechanism returns to the -30° position at which time it snap breaks with strip 49 and snap makes with strip 48. The object of holding arm 90 37 in contact with strip 49 until the mechanism has returned almost to its -40° position, is for the purpose of enabling the armature of the motor to attain sufficient speed to generate sufficient current to properly 95 energize the core 1 of the electric lock through a circuit to be later described.

Operation.—Upon raising the latch attached to the mechanical interlocking lever machine to the rocker of which sector 8, by 100 means of link 9 is connected, a partial movement is given to sector 8 and upon reversing the said lever and dropping the latch, a further movement is given to sector 8, as is well understood in the art and by so doing, arms 10, 11 and 12 actuated by the sector 8 are moved from the position shown to a position coinciding with dash lines drawn to an angle therewith thus placing arm 10 in contact with strip 13 whereupon

current will flow from the positive side of the battery 51 through wires 52 and 53 to arm 10, contact strip 13, to wire 54, wire 55, arm 33, contact strip 38, wire 56, wire 57, strip 48, arm 37, wires 58, 59 and 60 to arm 115 30 which is in the position shown at such time, through field coil 28 to brush 61, through the armature 26 to brush 62, to wires 63, 64, 65 and 66 to the other terminal of the battery 51. The current in the 120 above traced path passing through the motor causing the armature 26 of the same to rotate and move the signal mechanism from its -40° position to its 0° position, at which time arm 37 will break contact with strip 48 and snap into contact with strip 49. During the movement of the mechanism from its -40° position to the 0° position, the arm 35 will contact with strip 42 at the -3° position to the -1° position and as

that time arm 37 is in contact with strip 48 current from the battery 51 will also flow from wire 58 to wires 67 and 68 to strip 42, then through arm 35 to wire 69 to and through coils 23 and 24 on the hold clear device and then again unite with the current which is flowing through the motor and flow through wires 65 and 66, to the negative terminal of the battery 51. The current in this last above traced path flows through the low resistance coils of the hold clear device thus lifting the armature 21 throwing the hold clear device into contact with the signal mechanism which of course occurs just before the signal mechanism reaches the 0° position so that the hold clear mechanism is in a position to hold the signal mechanism in its moved position at the time it reaches the 0° position. At the same time the above operation is taking place, arm 36 comes into engagement with strip 45 at the -8° position of the signal mechanism and by so doing allows current to flow from wire 54 through wire 70, strip 45, arm 36, and wire 71 to and through the high resistance coils 25 and 22 of the hold clear mechanism, and then after flowing through the low resistance coils 23 and 24, it returns to the negative terminal of the battery by means of wires 65 and 66. The object of causing current to flow in the last traced path is to retain the hold clear mechanism in its moved position with the consumption of the least possible amount of current, which is accomplished by inserting in the circuit the considerable resistance of the coils 22 and 25. It is also to be observed that at the 0° position of the signal mechanism, the arm 35 has broken contact with strip 42 so that there is not a direct path from one side of the battery to the other side of the battery through the low resistance coils 23 and 24. At the same time that arm 10 was moved in contact with strip 13, the arm 12 was moved in contact with strip 15 and if relay 31 were energized, its armature 72 would be in the position shown, that is, using the signal vernacular it would be "picked-up", thus allowing current to flow from the positive terminal of the battery 51 through wires 52 and 73 to arm 12, to strip 15, through wire 74 to and through armature 72, to wire 75, through wires 76, 77 and 78, to strip 49, then to and through arm 37 and by means of wires 58, 59 and 60 to arm 30, through the field 28 of the motor to brush 61, to and through armature 26 to brush 62 and then by means of wire 63, 64, 65 and 66 to the negative terminal of the battery 51. Current in the above traced path would cause the signal arm 27 to be moved from its zero degree to its 45° position and in so doing, arm 33 would break contact with strip 38, arm 34 would come in contact with strip 41, from the 25° position of the blade to the 44° position of the blade for a purpose

to be later described. From the 42° position of the blade to the 44° position of the blade the arm 35 would contact with strip 43 thus allowing current to flow from wire 58 through wires 67, 79, and 80, to strip 43 through arm 35 to wire 69 and then through coils 23 and 24 to wires 65 and 66 to the negative terminal of the battery 51, thus picking up armature 21 in the same manner as heretofore described having been meanwhile dropped by the breaking of contact between arm 36 and strip 45 and just before the blade has actually reached the 45° position the arm 36 will come in contact with strip 46 allowing current to flow from wire 76 through wire 81 to strip 46, through arm 36 and through wire 71 to coils 25 and 22 and then through coils 23 and 24 and then through wires 65 and 66 to the negative terminal of the battery, thus holding the armature 21 in its moved position in the same manner as heretofore described.

If at the time the last described operation has taken place the armature 82 is "picked-up", a circuit will be formed as follows: positive terminal of the battery 51, wires 52 and 73, arm 12, contact strip 15, wire 74, armature 72, wires 75 and 83, armature 82, wires 84 and 85, strip 50 with which the arm 37 is at that time in contact, arm 37, wires 58, 59 and 60, arm 30, field coil 28, brush 61, armature 26, brush 62, and wires 63, 64, 65 and 66 to the negative terminal of the battery 51. The current in the above traced path causes the armature 26 to rotate and through the train of gears to move the signal arm 27 to the full clear or 90° position and in so doing causes arm 37 to break contact with strip 50, thus breaking the motor circuit heretofore described, but when the signal arm is moved between the 87° position and the 89° position, arm 35 contacts with strip 44 so that current may flow from wire 58 through wires 67, 79, and 86 to strip 44, arm 35, wire 69, coils 23, and 24, and wires 65 and 66 to the negative terminal of the battery 51, so that in the same manner as heretofore described the armature 21 will be picked up and at the time the signal reaches the full clear or 90° position the arm 36 will have moved into contact with strip 47 so that current may flow through the following path from wire 84; wire 87, strip 47, arm 36, wire 71, coils 25 and 22, coils 23 and 24, and wires 65 and 66 to the negative terminal of the battery 51, the current in which path causes in the manner heretofore described, the armature 21 to be held in the moved position.

With all of the parts in the position which they will assume when the signal is in the 90° position, a dropping of relay armature 82 would cause the arm to fall to the 45° position for the current from the battery fed to

wire 87 and then through the hold clear device from wire 84 would cease. The signal in returning to the 45° position would not stop exactly at the 45° position, but would drop a little below it so that arm 37 would come in contact with strip 49, and current would be fed to the motor to rotate the armature in a direction to clear the signal through the same path that current was supplied to the motor to move the signal from the danger position to the 45° position. The object of allowing the signal to drop a little below the 45° position and then be moved toward the clear position is in order to have the hold clear device thrown into retaining position at a time when the signal arm has very little momentum. By this method of operation as heretofore described, the signal arm drops until blade 37 comes in contact with strip 49, is then moved toward the clear position again breaking contact with the operating contact thus cutting current off from the motor which again allows the arm to settle toward the danger position, but it has only a very slight arc, arising merely from the fact that the holding parts of the hold clear mechanism seldom exactly mesh, to settle through before the retaining mechanism actuated as heretofore described governed by arms 35 and 36 holds it in the moved position, so that by such means very little shock is given to the mechanism by the arm dropping from the full clear position to the 45° position.

If while the signal is in the 45° position the relay armature 72 drops, as it would do by the entrance of a train into a section controlling relay 31, the holding current in the retaining device, through the circuit heretofore described would be broken, the signal arm 27 would drop to the zero or danger position, but in order to prevent shock to the mechanism by throwing in the hold clear device at the moment the arm reached the zero position, the mechanism is allowed to run a little below the zero position of the blade, so that arm 34 contacts with strip 40 thus allowing current to flow through the following circuit; positive side of battery 51, wires 52 and 53, arm 10, strip 13, wires 54 and 55, arm 33, wires 56 and 91, strip 40, arm 34, wires 90 and 60, arm 30, field coil 28, brush 61, brush 26, brush 62, and wires 63, 64, 65 and 66 to the negative terminal of the battery 51, which circuit is identical with the circuit formed to move the signal mechanism from the -40° position to the zero position, so that the armature 26 rotates and moves the arm toward the clear position, but as soon as the mechanism has arrived at the zero position, that is just to the position where a further movement will cause a movement of the blade, the arm 34 breaks contact with strip 40, but the signal mechanism is held in the moved position by

the pick-up circuits and the retaining circuits, through the hold clear device heretofore described.

The arm 37 has been herein described as moving over strip 49 synchronously with the movement of the blade. When the signal returns to the danger position by the entrance of a train into the section of track controlled by the signal and which itself controls relay 31, the armature 72 is caused to drop, but when the train leaves such section the armature 72 is again picked up and would consequently cause the signal to again move toward the clear position, such a signal is called a "non-stick" semi-automatic signal, but in a great many cases, perhaps the majority of cases, it is desired that the signal shall not again move toward the clear position upon the departure of a train from the section controlling the relay 31, such a signal is called a "stick" semi-automatic signal. A "stick" method of operation is obtained by holding the arm 37 in line with dotted line 92 when the signal returns to the danger position until the signal mechanism reaches the 30° position at which time the arm 37 is snapped from in contact with strip 50 to contact with strip 48, for by such a construction when the signal arm 27 has dropped to the zero or danger position the arm 37 is not in contact with strip 49, so that even if relay 31 picks up its armature 72 no path is available for actuating current to pass through the motor armature and fields of the signal motor and such a construction is not a departure from this invention but due to a mere arrangement of the parts of the circuit breaker shown and described in the application of Winthrop K. Howe, Serial No. 609,417. The strip 41 is for use with a "stick" semi-automatic signal where it plays a double function, for without it, if, while the signal arm was in the 45° position, the relay 31 should drop its armature 72 momentarily on account of some mechanical disturbance in the vicinity, or a reversal of polarity in the track circuits where polarized track circuits are employed, the retaining circuit through the hold clear device would be broken, consequently the arm would start to drop, but as the arm 37 is latched up and would not make contact with strip 49, the arm would move to the zero position and would stay at the zero position notwithstanding the fact that the relay 31 would have its armature 72 picked up again, and the signal arm should be in the 45° position, but with it the signal will be returned to 45° as soon as the relay which was temporarily on open circuit is again energized, for the movement of the signal toward the danger position from the 45° position would bring arm 34 into contact with strip 41, and current would be fed through the motor to rotate the armature if

a direction to clear the signal through the following path: positive side of battery 51, wires 52 and 73, arm 12, strip 15, wire 74, armature 72, wires 75, 76, 77 and 89 to strip 41, arm 34 and wires 90 and 60, to arm 30, field coil 28, brush 61, armature 26, brush 62 and wires 63, 64, 65 and 66 to the negative terminal of the battery 51. The current would move the signal to the 45° where it 5 would be held by the retaining device. The other function performed by strip 41 is to serve as an operating contact for the signal to close when moving from the 90° position to the 45° position. In case a "stick" 10 signal is used the arm 37 will be latched up so that it cannot contact with strip 49 only when rapidly passing over it after the arm has reached danger position and the mechanism has revolved to 80° position, 15 consequently strip 41 is added to catch the arm when falling from 90° position to 45° position, serving the function of strip 49 in catching the signal in a "non-stick" signal, and it serves current to the motor 20 25 through the circuit above traced. It is also to be noticed that both in the case of the arm 34 contacting with strip 41 and also with strip 40, when the arm 27 moves toward normal, due to the reluctance of the pick up circuit 30 for the retaining device, the armature 21 is not lifted until arm 27 is stopped. The interval of time is of course extremely slight but sufficient for the purpose. If in practical operation it does not prove sufficient 35 the length of the strips 41 and 43 can be adjusted to make it sufficient, by causing 35 to contact with 43 just a slight fraction of a second after 34 contacts with 41, so that the hold clear device will not be 40 picked up until the signal arm begins to move to clear position.

If the signal has returned to the danger position in the manner heretofore described, and if at that time the circuit is broken between arm 10 and strip 13, by the lifting of the latch on the lever of the mechanical interlocking machine and the return of the lever to approximately normal position, then the retaining circuit through the 50 hold clear device will be broken and the signal mechanism by means of the power storing device fully illustrated and described in application Serial No. 609,417 heretofore referred to, will be returned to 55 the 40° position, driving motor armature 26 backwardly at a very rapid rate of speed, which will cause a current to be generated therein, which flows through following circuit: armature 26, brush 62, wires 63, 64 and 65, helix 2, wire 93, arm 11, which is now 60 in contact with strip 14 due to the movement of the sector, wire 94, wire 55, arm 38, strip 38, wires 56 and 57, strip 48, arm 37 which makes contact with strip 48 at the 65° position of the signal mechanism, when

going backward as heretofore described, wires 58, 59 and 60, arm 30, field 28 and brush 61 to the other terminal of the armature 26, thus completing the circuit. The current flowing in the above traced circuit 70 and generated by the revolution of the armature 26, energizes the helix 2, magnetizes the core 1 and attracts the armature 3 which moves the dog 7 out of engagement with shoulder on the sector 8, allowing the latch 75 17 to move under the dog 7, so that at any future time the sector 8 may have its movement completed so that the mechanical locking in the interlocking machine of which the lever and latch controlling the sector 8, so is a part, may be properly actuated.

As a spring occurs between two parts of the snap circuit breaker of which the arm 37 is one part, there is a remote possibility that the said spring may break, and if it 85 did break, the arm 37 would not be moved at all by the movement of the signal actuating mechanism so that if the signal actuating mechanism was in the normal position and current was supplied to it from the circuit 90 heretofore described, the armature of the motor would be caused to rotate and would rotate as long as current was supplied to said circuit causing the signal arm to be moved to the full clear or 90° position irrespective of the position of the armatures 72 and 82, but as such a contingency could not be tolerated, the arm 33 and strip 38 have been placed in the circuit so that if arm 37 could remain in the position as shown in the 100 figure and be incapable of moving from such position the signal arm could not be moved to the full clear position by supplying current to the circuit heretofore described which is merely designed to carry 105 current to move the signal mechanism to the 0° position, for, as soon as the signal blade moved 3° from the zero degree position, the arm 33 would break contact with strip 38 and the motor would stop as the current to 110 the motor would be cut off and the blade would drop back until held by the energization of the hold clear mechanism through contact 45. Arm 33 would under such conditions make contact with strip 38, so that 115 the blade would again be moved 1° and would again drop back, thus seesawing back and forth in an arc of about 1° plus the amount of unavoidable looseness in the parts.

As fully shown and described in application 531,264, heretofore referred to, the arm 30 is caused to contact with wire 95 momentarily just before the signal arm reaches the 45° position and just before it reaches the zero 125 degree position in dropping from the clear position toward the zero degree position, so that the motor, including its field and armature in series are short circuited upon themselves, thus forming in effect an electrical 130

dash-pot to dampen the downward movement of the blade.

Having thus fully described one particular arrangement and combination of elements illustrating the principle of my invention, what I claim and desire to secure by Letters Patent, is:

1. In a signal mechanism, a signal having a normal position, a full clear position and an intermediate position, and a bias to normal position, a motor for operating said signal having an armature, said armature revoluble by the signal when moving toward normal position, a source of energy, means for causing energy to be supplied to said motor to move said signal to the full clear position, and for causing energy to be supplied to said motor from said source to move said signal toward said full clear position just after the signal has passed beyond the intermediate position in going toward the normal position, and means thereafter actuated to hold said signal in the intermediate position, an indication device, and conductors between the motor and the indication device for allowing the current generated by the revolution of the armature of the motor to energize the indication device.
2. In a signal mechanism, a signal having a normal position, and an operated position, and a bias to the normal position, a motor having an armature for operating said signal, said armature having three positions and connected to the signal by a connection allowing independent movement, one of said positions being an intermediate position corresponding to the normal position of the signal, a source of energy and means for supplying energy to said motor from said source, to move said motor to said intermediate position just after the motor has passed beyond the said intermediate position caused by the signal going to the normal position, and means thereafter actuated to hold said motor in the said intermediate position.
3. In a signal mechanism; a signal having a normal biased position and an operated position; a source of current; a motor for moving the signal to the operated position; two normally open circuits including the source of current and the motor; means for closing said circuits; two circuit controllers operated by the signal; both in-

cluded in one of the normally open circuits and one included in one only of said circuits, the one of said circuit controllers included in one only of said circuits adapted to break the circuit containing both of the circuit controllers upon a slight movement of the signal from the normal position, the other circuit controller adapted to break the other circuit about at the operated position of the signal.

4. In a signal mechanism; a signal having a normal biased position and an operated position; a power storing device; means connecting the signal, the motor and the power storing device, whereby the rotation of the motor in one direction charges the power storing device and then moves the signal to the operated position, and the movement of the signal in response to its bias rotates the motor and after the signal reaches normal position the power storing device continues the rotation of the motor; a source of current; manually controlled circuit controllers; circuit controllers operated by the movement of the signal; a circuit controller operated by the signal after a predetermined movement of the signal; connections including a manually controlled circuit controller, the source of current, the motor, and the signal operated circuit controllers for allowing current to flow from the source for operating the motor during its period in which it charges the power storing device; connections including another manually controlled circuit controller, the circuit controller operated by the signal after a predetermined movement, the motor, the source of current, and one of the signal operated circuit controllers for allowing current to flow from the source to continue the rotation of the motor for moving the signal to the operated position; an indication lock; connections including another manually controlled circuit controller, the indication lock, certain of the signal operated circuit controllers, and the motor in which indication current flows by reason of the rotation of the motor due to the power storing device; and means for controlling the manually operated circuit controllers controlled by the indication lock.

WILLIAM S. HENRY.
